UNITED STATES PATENT OFFICE.

ADOLPH F. ROTH, OF NEWARK, NEW JERSEY.

EXHAUST FAN.

1,409,199.

Specification of Letters Patent. Patented Mar. 14, 1922.

Application filed April 15, 1920. Serial No. 374,130.

To all whom it may concern:

Be it known that I, ADOLPH F. ROTH, a citizen of the United States, and a resident of Newark, in the county of Essex and State of New Jersey, have invented certain new and useful Improvements in an Exhaust Fan, of which the following is a full, clear, and exact specification.

This invention relates more particularly to 10 a class of ventilating devices.

My invention has for its object primarily to provide a fan designed to be employed for ventilating compartments of houses, stores, factories, ships, underground chambers of mines and elsewhere so that foul atmosphere produced by being excessively charged with gas, acid fumes, heat, smoke and other foreign products may be effectually exhausted, in order that the atmosphere may be kept free from injurious contamination. The invention consists mainly of the provision of a tube having an inlet and an outlet, and this tube is adapted to be supported so that its inlet leads from a compartment or air chamber which is susceptible of being charged with impurities. At the outlet of the tube is provided an electrically operative motor having its drive shaft revolvable at the outlet, and on the motor shaft at the outlet of the tube is a suction-fan for being driven with the rotation of the shaft. Between the fan and the motor is a deflector for causing the air exhaust from the chamber through the tube to be discharged from the outlet in a manner to prevent the motor being contacted by the air exhaust which when charged with acid fumes or smoke or moisture or gas will tend to damage the motor.

Another object of the invention is to enclose the motor in a cooling chamber or hood having spaced outlets so arranged that partial vacuums will be produced by the driving of the fan and force of discharge of the exhaust to cause the heat in the hood when generated by the operation of the motor to be suctionally discharged from the hood in order to prevent the motor from becoming excessively heated.

A further object of the invention is to provide an exhaust fan of a simple, efficient and durable construction which may be made of any suitable material in various sizes and shapes.

With these and other objects in view the invention will be hereinafter more fully de-

scribed with reference to the accompanying drawing forming a part of this specification in which similar characters of reference indicate corresponding parts in all the views, 60 and will then be pointed out in the claims at the end of the description.

In the drawings, Figure 1 is a fragmentary view, partly in section, showing an elevation of one form of exhaust fan embodying my invention and the manner of its use for ventilating a compartment of a building or other structure.

Fig. 2 is an enlarged detail sectional view, partly broken away, taken through the fan, and

Fig. 3 is an enlarged plan, partly fragmentary, of the fan with its cooling hood removed therefrom.

The fan has a tube 10 which may be of any suitable size and shape, though the tube illustrated is cylindrical and one end of the tube serves as an inlet 11, while its other end serves as an outlet 12. When the fan is employed the inlet end of the tube is arranged in an opening, as 13, provided in an appropriate part of the wall or roof, as 14, of the compartment or chamber, as 15, of a house, store, factory, ship or mine which is to be ventilated, and the tube is preferably of a length so that its inlet end 11 extends interiorly of the compartment, while its outlet end terminates some distance beyond the wall or roof. Exteriorly of the outlet end 12 of the tube may be an annular flange 16, and the tube may be securely supported on the wall or roof by a number of spaced bars 17. These bars are disposed in downward diverging arrangement exteriorly of the tube, and the upper ends of the bars are fastened to the flange 16 of the tube, while their lower ends are fastened to the wall or roof 14.

Above the outlet 12 of the tube 10 is a motor 18 which may be of any well known or preferred type adapted to be driven by electric current delivered thereto over wires, as 19, leading from any suitable source of electricity supply. The motor is arranged so that its drive shaft 20 is disposed toward the center of the outlet 12 of the tube 10, and the motor is supported on the tube by a bracket, as 21, which preferably consists of a ring or band 22 arranged so that it fits closely around the casing of the motor. To this band is connected the upper ends of a number of spaced downwardly curved bars

or legs 23 having their lower ends fixed to the flange 16 of the tube 10.

Adapted to be rotated with the driving of the shaft 20 of the motor is a fan 24 which is of a suction type having blades, as 25, which are preferably of forms corresponding approximately to the types of blades disclosed in my Patent Number 1,213,955. These blades of the fan are arranged as well as being of sizes so that they will freely revolve within the outlet of the tube whereby a partial vacuum in the tube will be produced to cause the air with its impurities to be freed from the chamber 15 by being suctionally forced through the tube and discharged through the outlet of the tube. The blades 25 of the fan are mounted on a plate 26 which also serves as a deflector for preventing the air products 20 exhausted through the outlet 12 of the tube from contacting with the motor, in order, that liability of premature damage to the motor will be prevented especially in instances where the air is charged with acid 25 fumes or smoke or gas or other foreign substances likely to affect the parts of the motor. The deflector or plate 26 is held on the drive shaft 20 of the motor so that it is spaced a distance from the end of the 30 tube 10 providing the outlet 12, and this plate is preferably circular as well as being of a diameter approximately similar or slightly larger than the outlet of the tube. The air when discharged from the outlet 35 of the tube by employing the deflector or plate in this manner will be forced from the outlet between the tube and the plate in lateral directions relative to the tube, and the motor will thereby be protected from 40 subjection to the air products.

Serving to keep the motor cool during its operation, I may provide a cooling chamber or hood, as 27. This cooling hood may be of any appropriate form, though the 45 hood shown is preferably composed of a body part, or cap 28 having a cone-shaped top 29 with an annular flange 30 depending from its peripheral edge, and at the lower edge of this depending flange may be an 50 outwardly flared flange, as 31. The underside of the cap 28 is closed by a plate, as 32, which extends crosswise interiorly of the flared flange 31. The hood 27 is arranged so as to inclose the motor 18 by being disposed thereover with the legs 23 of the bracket 21 passing through spaced openings, not shown, in the plate 32. The plate 32 may be arranged on the legs of the bracket 21 separate of the cap 28, after which the 55 cap and plate may be soldered or otherwise secured together. Leading from the interior of the hood 27 are a number of spaced outlets, as 33, which are in the forms of tubular members each having one of its ends 60 disposed in an opening in the depending 65 flange 30 of the cap 28 of the hood 27. These tubular members are also disposed on top of the flared flange 31 of the cap of the hood as well as being of lengths so that their second ends overhang the free edge of the 70 flared flange. The flared flange 31 of the cap of the hood is of a diameter whereby the overhanging ends of the tubular outlets 33 of the hood are disposed with relation to the tube 10 of the device so that 75 the force of the exhausted air products discharged through the outlet 12 of the tube will when the fan is in operation produce by its suction partial vacuums in the tubular outlets for causing the atmosphere in the 80 hood when heated by the motor 18 to be suctionally drawn therefrom through the outlets 33 of the hood.

In the foregoing description, I have embodied the preferred form of my invention, 85 but I do not wish to be understood as limiting myself thereto, as I am aware that modifications may be made therein without departing from the principle, or sacrificing any of the advantages of this invention, 90 therefore, I reserve to myself the right to make such changes as fairly fall within the scope thereof.

Having thus described my invention, I claim as new and desire to secure by Letters 95 Patent:—

1. In a ventilating device, in combination, a tube having an inlet and an outlet, adapted to be supported so that its inlet leads from an air chamber, a suction fan rotatably 100 driven by a motor within the outlet of the tube, and a hood having a closed underside supported in spaced relation to the outlet of the tube and inclosing the motor, said hood having an inlet and having spaced outlets arranged circumferentially of the outlet of the tube so that partial vacuums will occur in the outlets with the driving of the fan and discharge of the exhaust to cause the 105 heat in the hood when generated by the operation of the motor to be suctionally discharged from the hood through its outlets.

2. In a ventilating device, in combination, a tube having an inlet and an outlet, adapted to be supported so that its inlet leads from 115 an air chamber, a suction fan rotatably driven by a motor within the outlet of the tube, a deflector between the fan and motor for causing the air exhaust from the chamber through the tube to be discharged from the 120 outlet of the tube whereby the motor will be protected against contact by the air exhaust, and a cap supported above the deflector in spaced relation to the outlet of the tube and inclosing the motor, said cap having an inlet and having spaced outlets arranged circumferentially of the outlet of the tube so that partial vacuums will occur in the outlets with the driving of the fan and discharge of the exhaust to cause the heat in 125 130

the cap when generated by the operation of the motor to be suctionally discharged from the hood through its outlets.

3. In a ventilating device, in combination,
- 5 a tube having an inlet and an outlet, adapted to be supported so that its inlet leads from an air chamber, a suction fan rotatably driven by a motor within the outlet of the tube, and a plate between the fan and motor
- 10 for causing the air exhaust from the chamber through the tube to be discharged from the outlet of the tube whereby the motor will be protected against contact by the air exhaust.
- 15 4. In an exhaust fan, the combination with the outlet of a chamber, of a hood supported in spaced relation to the outlet and having a closed underside, a motor in the hood, a suction fan carried by the motor for being
- 20 driven between the underside of the hood and the outlet of the chamber, said hood having an inlet and having spaced outlets above and surrounding the outlet of the chamber so that partial vacuums will occur in
- 25 the spaced outlets with the driving of the fan

and discharge of the exhaust to cause the heat in the hood when generated by the operation of the motor to be suctionally discharged from the hood through its outlets.

5. In an exhaust fan, the combination with 30 a motor and a suction fan adapted to be supported above the outlet of a chamber, of a hood surrounding the motor above the fan, and having a closed underside, said hood having an inlet and having spaced outlets 35 arranged circumferentially above the outlet of the chamber so that partial vacuum will occur in the spaced outlets with the driving of the fan and discharge of the exhaust to cause the heat in the hood when generated 40 by the operation of the motor to be suctionally discharged from the hood through its outlets.

This specification signed and witnessed this 14th day of April A. D. 1920.

ADOLPH F. ROTH.
